UNITED STATES PATENT OFFICE.

JOHN GILSON, SR., OF PORT WASHINGTON, WISCONSIN, ASSIGNOR TO GILSON
MANUFACTURING COMPANY, OF PORT WASHINGTON, WISCONSIN.

PINTLE ATTACHMENT FOR MACHINE ELEMENTS.

1,162,477.

Specification of Letters Patent. Patented Nov. 30, 1915.

Application filed February 13, 1915. Serial No. 7,997.

To all whom it may concern:

Be it known that I, JOHN GILSON, Sr., a citizen of the United States, and resident of Port Washington, in the county of Ozaukee and State of Wisconsin, have invented certain new and useful Improvements in Pintle Attachments for Machine Elements; and I do hereby declare that the following is a full, clear, and exact description thereof.

10 My invention has for its object to provide a simple, economical and effective fulcrum anchor for oscillatory machine elements, the same being especially applicable to fly-wheel governors.

15 The construction and arrangement of my invention are such that the machine work ordinarily necessary for fitting the fulcrum element is eliminated, it being usual in the type of governors to which my invention especially refers, to cast ears from the spokes of the fly-wheel, which ears are then bored for the reception of a fulcrum pin. The boring operation, owing to the position of the ears and the various sizes of fly-wheels, thus

20 causes considerable skill and expenditure of time in completing the operation with tools of ordinary construction. It is obvious, however, that my peculiar arrangement of attaching the anchor pin employed in the

25 construction of various machine elements will overcome the above objectionable features as the parts can all be assembled without recourse to machining or fine adjustment.

30 With the above objects in view the invention consists in certain peculiarities of construction and combination of parts as hereinafter set forth with reference to the accompanying drawings and subsequently claimed.

35 In the drawings Figure 1 represents an elevation of a fly-wheel provided with a governor fulcrum pin attached in accordance with my invention, parts being broken away and parts in section, as indicated by lines 1—1 of Figs. 2 and 3; Fig. 2, a detailed face view of a fragment of the fly-wheel, partly in section, as indicated by line 2—2 of Fig. 1; Fig. 3, another detailed sectional view, the same being indicated by line 3—3 of Fig. 2, and Fig. 4, an enlarged detailed sectional view showing the anchor-pin construction, the same being indicated by line 4—4 of Fig. 2.

40 While I have shown an exemplification of

my invention associated with a governor-controlled fly-wheel, it is obvious that the same may be employed in connection with various machine elements.

Referring by characters to the drawings, 45 Fig. 1 represents a fragment of a bed carrying a journal-box, in which is mounted a shaft 2 having keyed thereto a fly-wheel 3 and loosely mounted thereon a sleeve 4, which sleeve is adapted to control a knock-off lever 5 that constitutes part of a valve tripping mechanism for an internal combustion engine, not shown. The sleeve is longitudinally shifted upon the shaft by a spring-controlled governor arm 6, which governor arm is loosely fulcrumed upon a pivot-pin 7 that is attached to companion spokes 3' of the fly-wheel, the same constituting a base member. The companion spokes are cast with raised pads 8, 8, which are spaced apart to 50 form a socket for the apertured hub 6' of the governor arm, the same being, as previously stated, loosely mounted upon the fulcrum pin 7. The fulcrum pin, as shown, is seated in interrupted or companion V-shaped 55 grooves 9, which grooves intersect circular apertures 10 that extend through the pads and fly-wheel arms. These apertures, owing to their convenient and accessible alinement, may be bored in some instances, or cored as 60 conditions warrant. The pivot-pin, which is circular in cross-section, is provided with squared ends that are alined with the inner opposite walls of the apertures 10, whereby 65 said apertures present unobstructed passages for bolt elements 11, having squared shanks 11', faces of which abut the squared ends of the pivot-pins, as shown. The bolt elements are also provided with suitable heads 11'', which, as best shown in Fig. 4, overlap and 70 impinge the circular faces of the pivot-pin ends and, owing to the fact that the squared ends of said pivot-pins also abut the squared shanks 11' of the bolt elements, it will be observed that said bolt elements are held 75 against twisting in their retaining apertures when they are drawn up by the usual binding washers and nuts 13, which elements abut the opposite faces of the spokes, as best 80 shown in Fig. 3. Thus it is apparent that 85 the V-shaped groove seats 9 for the pivot-pin, in conjunction with the bolt-heads 11', form a three-point bearing for said pivot-pin, whereby the latter is firmly gripped at its 90 ends and is thus held against twisting. This 95 100 105 110

construction requires no machine work as the seat and apertures may be roughly cast, ready for the reception of the pin without further finishing. Hence it will be seen that the construction as exemplified is both simple and durable and can be manufactured at a minimum cost.

While I have shown the seating grooves 9 as being preferably V-shaped in cross-section, it is obvious that these grooves may be of any design other than that shown without departing from the spirit of my invention and attention is also directed to the fact that the anchor-pin projects slightly above the faces of the pads, whereby a positive firm grip is insured as there is sufficient clearance between the bolt-heads and said pad faces to permit all of the draw necessary to clamp the parts tightly to the surfaces engaged by said pin. It is also apparent that, while I have shown bolt elements separable from both ends of the pin 7, I may, in some instances, form one of the bolt elements as a right-angle continuation of the pin, for accomplishing the same result and the invention may be carried out by various other modified forms, the essential feature being the grooved seat with a bolt element for clamping the pivot-pin firmly within its seat.

I claim:

1. An anchor-pin attaching means comprising a base having an aperture therein, and a grooved seat intersecting the aperture, a pivot-pin seated within the groove, a confining bolt member for the pin extending through the aperture, and a nut engaging the bolt end, whereby the pivot-pin is caused to grippingly engage the seat groove.
2. An anchor-pin attaching means comprising a base having companion apertures therein, an interrupted groove intersecting

the apertures, a pivot-pin seated within the groove terminating at the apertures, and headed confining bolts for engagement with the pin ends extending through the apertures.

3. An anchor-pin attaching means comprising a base having companion circular apertures therein, an interrupted groove intersecting the apertures, a pivot-pin seated within the groove terminating at the apertures, and headed confining bolts for engagement with the pin ends extending through the apertures, the bolts being provided with squared shanks, faces of which abut the ends of the pin, and an arm loosely mounted upon the pin between the grooves.

4. An anchor-pin attaching means comprising a base having an aperture therein, a V-shaped groove intersecting the aperture, a pivot-pin seated within the groove, a confining bolt member for the pin extending through the aperture, and a nut engaging the bolt end, whereby the pivot-pin is caused to grippingly engage the seat groove.

5. An anchor-pin attaching means comprising a base having companion apertures therein, interrupted V-shaped grooves intersecting the apertures, a circular pivot-pin seated within the grooves, confining bolts having heads for engagement with the ends of the pivot-pin extending through the apertures, and securing nuts for said bolts.

In testimony that I claim the foregoing I have hereunto set my hand at Port Washington, in the county of Ozaukee and State of Wisconsin, in the presence of two witnesses.

JOHN GILSON, Sr.
